ELECTRIC RECEPTACLE

Glenn E. Blinn, Leonia, N. J.

Application April 30, 1938, Serial No. 205,160

12 Claims. (Cl. 173—328)

This invention relates to electric receptacles, and more especially to the safety type in which it is difficult or impossible to make accidental contact with live parts of the receptacle.

Electric receptacles of this nature have heretofore been proposed, but they included either the disadvantage of requiring a special type of plug which could not be used with the ordinary non-safety type of receptacle or else the disadvantage that the insertion and removal of the plug could be effected only in two stages, one of which involved a twisting motion, with the result that persons unfamiliar with such devices experienced difficulty in using them.

On the other hand, the electric receptacle according to my invention is adapted to receive any standard plug having two or more connection prongs which may be inserted and removed by simple pushing and pulling motions, as in the case of the common non-safety receptacle. Yet this receptacle provides a door, or doors, effectively closing the holes provided to receive the connection prongs of a complementary plug, except when at least two such prongs are simultaneously inserted in those holes. Thus it is impossible for children, for example, to insert a metallic object far enough into the receptacle to make connection with a contact spring or other live part thereof with the likely result of suffering electric shocks or burns.

To this end my invention provides at least one lock for each door, the locks being released by trips in the prong-receiving holes. The trips and locks are so related with respect to the holes and doors that the insertion of an object into only one hole will not open the door which closes that hole. By "doors" is meant the means which serve effectively to close the holes whether they are individual to each hole or constructed as a single unit.

Three adaptations of a preferred embodiment of the invention are described in the following specification, and are illustrated in the drawings wherein Figs. 1-7 illustrate one adaptation, Figs. 8-21 a second, and Figs. 22-28 a third. More specifically:

Fig. 1 is a view of a longitudinal section taken along the line 1—1 of Fig. 2;

Fig. 2 shows a transverse section taken along the line 2—2 of the complete receptacle of which Fig. 1 is a sectional view;

Fig. 3 is a sectional view similar to that of Fig. 1 after a two-prong attachment plug has been inserted in the receptacle;

Fig. 4 is a transverse view taken along line

4—4 of Fig. 1 of the complete receptacle of which Fig. 1 is a section; thus, Fig. 2 and Fig. 4 are in effect views of opposite ends of the receptacle;

Figs. 5 and 6 are sectional views which correspond to Figs. 1 and 3, respectively, taken after the receptacle has been turned 90° on its longitudinal axis, Fig. 5 being a longitudinal section taken along the line 5—5 of Fig. 2, and Fig. 6 being similar to Fig. 5, but having been taken after a two-prong attachment plug has been inserted; and

Fig. 7 is an end view of the shell formed to accommodate the receptacle mechanism.

The remaining figures will be referred to hereinafter in connection with the other adaptations.

Referring now to Figs. 1-7, inclusive, wherein like reference characters indicate the same parts, there is shown a containing shell 1 which preferably is of insulating material and shaped to conform to the outline of the receptacle mechanism. This mechanism includes the usual contact springs 5, 6, screwed or riveted to a supporting plate so as to be in alignment with holes 3, 4 pierced through one end of the shell. In the drawings this end is represented as a flat plate-like portion 2. These holes and their respective contact springs are spaced and proportioned to receive the connection prongs, or blades, of the standard two-prong attachment plug, such as is shown at 23 in Fig. 3 and Fig. 6. The invention is, however, adapted to be applied to receptacles intended for use with plugs having more than two prongs, as will hereinafter be explained.

Under each of holes 3 and 4 is hinged a door, or shutter 7, 8 which, when in the position shown in Figs. 1, 2 and 5, effectively closes the hole at the bottom and prevents any object inserted in the hole from touching a contact spring or other live part of the receptacle. This is true because both doors 7 and 8 are hinged on pins 17 and 18, and neither one can be swung on its hinge toward the center of the receptacle while either of dogs 11 and 12 is between them. However, as both prongs of an attachment plug 23 are inserted through holes 3 and 4 the releasing means 45 or trips 9 and 10, one for each hole, are pressed down through an angle of about 40°, swinging the attached dogs 11 and 12 away from the center and allowing the heels of both doors to move toward each other, as shown in Figs. 3 and 6, 50 into the space previously occupied by the dogs. Accordingly, prongs 25 and 26 of the attachment plug can then pass by the doors and engage the contact springs 5 and 6 in the usual manner.

Upon withdrawal of the plug 23, doors 7 and 8

will be restored to their original position, closing the holes, by reason of the action of springs 13 and 14. These springs are anchored at one end to fixed pins 19 and 20, and at the other end are secured to pins 21 and 22 passing through the slotted rear portions of dogs 11 and 12. These springs, therefore, tend to urge the dogs toward the center and each other, and the dogs, in turn, press against the heels of the door members which are thereby returned to the closed position.

From the foregoing description it will be apparent that the insertion of an object into either of the holes 3 and 4 can at most move only one of the two dogs, but since each dog is effective to lock both doors in closed position neither door will thereby be released. Furthermore, it will be seen that in order to release and open either door, both dogs must be moved away from their locking position and that, to accomplish this, both releasing trips 9 and 10 must be pressed down a sufficient distance, as by the simultaneous insertion of both prongs of a standard attachment plug.

In the above-described adaptation, as well as in the other adaptations hereinafter described, the receptacle is illustrated in the form known as a "separable connector", suitable, for example, to connect the ends of flexible extension cords. End cap 24 is therefore provided to cover the terminal screws 15 and 16 to which may be attached the wires of a flexible cord passing through hole 35. The flexible cord which would be connected to the attachment plug 23 would pass through a corresponding hole (not shown) in the plug. Screws 29 and 30 serve to attach cap 24 to the body of shell 1, and screws 27 and 28 secure the receptacle mechanism in the shell 1. However, such details are shown merely by way of example, since any desired fastening means can be employed, and the receptacle mechanism may obviously be secured in the usual wall outlet box or any suitable container wherein such device is desired.

The second adaptation incorporates the invention in a receptacle designed for use with an attachment plug of the polarized type. The prongs of a polarized plug are usually at right angles instead of parallel to each other. (If the prongs are merely of different shapes or sizes, the above-described mechanism may usually be employed.) The receiving holes in the face of the receptacle must, therefore, be similarly arranged.

Referring now to the drawings of the second adaptation of the invention:

Fig. 8 is a view of a longitudinal section taken along the line 8-8 of Fig. 9;

Fig. 9 shows a transverse section taken along line 9-9 of the complete receptacle of which Fig. 8 is a sectional view;

Fig. 10 is a sectional view similar to that of Fig. 8 after a two-prong polarized attachment plug has been inserted in the receptacle;

Fig. 11 is a sectional view taken at the line 11-11 of Fig. 9;

Fig. 12 and Fig. 13 are views of opposite ends of the receptacle with the end cap removed.

Certain details of the mechanism are shown in Figs. 14-21 as follows:

Fig. 14 shows the mechanism at line 14-14 of Fig. 9, and Fig. 15 is a similar view after the prongs of an attachment plug have been inserted;

Fig. 16 shows the mechanism at line 16-16 of Fig. 9, and Fig. 17 is a similar view after the

prongs of an attachment plug have been inserted;

Fig. 18 is a view of the mechanism at line 18-18 of Fig. 9, and Fig. 19 is a similar view after the prongs of an attachment plug have been inserted;

Fig. 20 is a view of the mechanism at line 20-20 of Fig. 9, and Fig. 21 is a similar view after the prongs of an attachment plug have been inserted.

In this group of figures the same reference characters represent the same parts; and reference characters which also appear in the figures of the other groups of drawings represent corresponding parts.

In this adaptation the holes in the face of the receptacle are placed at right angles, as shown at 3 and 4 in Fig. 13, to accommodate the prongs of the polarized plug. Here the door 7 serves to close the hole 3 which is turned at right angles to the door 8 serving to close hole 4, as shown in Figs. 8-11. Because of this arrangement the doors cannot be assembled in the back-to-back relation shown in the preceding figures, from which it follows that different locking means must be employed. As before, however, there are two locking means associated with each door, only one of which is released by the insertion of one of the prongs in its hole. Beneath the hole 4 door 8 is hinged on pin 36. This door is locked against opening by two dogs 40 and 43. Dog 40 is secured to shaft 34 which is rotated by pressure on releasing means or trip 10, and dog 43 is attached to shaft 33 which is rotated by pressure on releasing means or trip 9. Therefore, when both prongs of the attachment plug are inserted in the holes 3 and 4, trips 9 and 10 are depressed, shafts 33 and 34 are rotated, and dogs 43 and 40 are swung away from each other, allowing the heel of door 8 to move into the space which the dogs formerly occupied, thus opening hole 4, and permitting access to contact spring 6. Door 7 is hinged on pin 46 which is at right angles to pin 36 for door 8. As before, this door is also locked by two separate locking means, one being actuated by the rotation of shaft 33 and the other by rotation of shaft 34. In this instance, however, the hinge pin 46 of the door is parallel to the dog-releasing shafts 33 and 34 which requires a different type of locking means. To this end, a latch 38 is secured to shaft 34 bearing on a shoulder at the rear of the door 7, as shown in Fig. 18, preventing the door from swinging toward the latch until the latch is turned away, as shown in Fig. 19. The second locking means for door 7 is shown more clearly in Fig. 18 to comprise a pin 39 secured near the face of the door, and a locking strap 41 which fits thereover. From a consideration of Figs. 18 and 19 it will be seen that when the locking strap is in the position shown in Fig. 18 the door 7 is also prevented from swinging (toward the left in the figures), but is permitted to do so when strap 41 is turned away as shown in Fig. 19.

Springs 13 and 14 are anchored at one end to anchor post 42, and at their other ends are secured respectively in ears 45 and 44 attached to shafts 33 and 34. By pulling on these ears the springs tend to hold dogs 40 and 43 in closed position as shown in Figs. 8 and 9, the dogs in turn tending to swing door 8 into its closed position. Likewise spring 14 tends to turn door 7 to its closed position by causing latch 38 to press against the back of that door.

Pin 37 serves to retain one end of the shaft 34, the other end of the shaft being retained by hinge 75

pin 36. Shaft 33 is retained at one end by being inserted in a hole in shell 1, and is retained near the other end by pin 63.

The third adaptation of the invention will now be referred to in connection with the remaining figures. It is useful either with the polarized or unpolarized type of attachment plug, but the drawings illustrate a receptacle intended for use with the unpolarized type such as illustrated in connection with the first adaptation. The third adaptation differs from the first two mainly in that the safety doors which close the prong-receiving holes are, in this instance, secured to or are an integral part of a single sliding member. The door surfaces are therefore caused to close and open the respective holes by a sliding motion, rather than by a rotating one as described above.

Referring to the drawings:

Fig. 22 is a view of a longitudinal section taken along the line 22-22 of Fig. 23;

Fig. 23 shows a transverse section taken along the line 23-23 of the complete receptacle of which Fig. 22 is a sectional view;

Fig. 24 is a sectional view similar to that of Fig. 22 after an attachment plug has been inserted in the receptacle;

Fig. 25 is a sectional view taken at line 25-25 of Fig. 23;

Fig. 26 is a sectional view similar to that of Fig. 25 after an attachment plug has been inserted in the receptacle;

Fig. 27 is a sectional view taken at line 27-27 of Fig. 23; and

Fig. 28 is a plan view of the sliding door member.

As shown in the figures, door faces 48 and 49 are, in this example, an integral part of the slide 47 which is urged in one direction by the compression spring 50. In Figs. 22, 23 and 27, doors 48 and 49 are shown closing holes 4 and 3, respectively, to prevent access to the contact springs 6 and 5. However, upon insertion of an attachment plug 23, the connection prongs 25 and 26 press down the releasing means or trips 9 and 10, rotating shafts 51 and 56 respectively, and lifting latches 51 and 52 from locking holes 53 and 54, respectively. Thus, as the connection prongs of the plug are inserted further into holes 4 and 3, they press against the cam-like door surfaces 48 and 49 and displace the slide member against the spring 50, effectively opening the doors by aligning hole 64 in the slide with hole 4 and by displacing the edge 65 of the slide beyond the hole 3, thus allowing the connection prongs to be inserted in contact springs 6 and 5.

Upon withdrawing the connection prongs of the attachment plug the reverse operation takes place, that is, as the ends of the prongs are drawn away from the door faces 48 and 49, spring 50 closes the doors by moving slide member 47 to its original position.

From Fig. 23 it will be seen that retaining plates 59 and 60 hold slide member 47 in operative position. By removing these plates slide 47 may be lifted out of its slideway. Shafts 56 and 57 are held in place by bearing blocks 62 and 61 respectively. When shafts 56 and 57 are rotated as the result of pressure upon trips 10 and 9, they are rotated against the action of springs 58 and 55, respectively. These springs encircle their respective shafts under tension, one end of each being secured to its shaft, and the other end being anchored to the corresponding bearing block as shown for example, in Figs. 23 and 27.

From the foregoing description of the mecha-

nism of Figs. 22-28, it is apparent that, like that of the other two adaptations above described, neither door can be moved to allow access to a contact spring or other live part of the receptacle until both releasing means 9 and 10 have been actuated. This is true because each of latches 51 and 52 serves to lock slide 47 in the closed position, and hence to lock both doors in closed position.

From the foregoing description of three adaptations of the present invention, those skilled in the art will understand how to modify the constructional details for various other adaptations. For example, three-wire cords and cables are frequently met with in practice, and require, of course, three-prong attachment plugs and three-contact receptacles. These are, in practically all cases, polarized so that the attachment-plug prongs can be inserted into the receptacle only in one way. If the third wire is grounded (as is frequently the case) it is not always necessary that a safety door be provided for the third hole of the receptacle because there would then be no potential difference between the grounded wire and any grounded object. In that event, therefore, safety doors can be provided for the other two holes of the receptacle according to any of the arrangements above described. If, however, it is desirable to provide a safety door for the third hole in the receptacle it can readily be added in any appropriate manner depending upon its physical position with respect to the other holes. The exact mechanical layout for the doors, the locks, and the lock-releasing means would then depend largely upon the angles between the various holes in the receptacle. However, the foregoing descriptions and drawings relating to mechanism adapted to receptacles having holes parallel and also holes at right angles to each other is sufficient to enable a worker in the art to apply the invention to receptacles having any number of holes and having holes at different angles. If there are an even number of holes it is usually convenient to arrange them in pairs following the designs above described. If there are an odd number of holes, there may still be releasing means associated with each hole, but these releasing means may conveniently be arranged to control a locking means on the door associated with the same hole simultaneously with the locking means on the door associated with an adjacent hole, and so on in seriatim, until the releasing means at the last hole controls the locking means associated with the door of that hole and the door of the first-named hole.

In any event, the receptacle should be provided with a safety door to close each hole beneath which there is a live contact, and, as a minimum requirement, each such door should be locked by at least one locking means which is released by a trip associated with another hole, i. e., the door and the trip which serves to release it should not be associated with the same prong-receiving hole. However, it is preferable to provide each door with at least two locking means, as above described in connection with three adaptations of the preferred embodiment of the invention.

What is claimed is:

1. In an electric receptacle having a plurality of holes adapted to receive the connection prongs of an attachment plug, a door portion and a trip associated with each hole, said door portion being provided with as many locking means as there are prong-receiving holes in said receptacle,

and means operatively connecting the locking means for the door portion associated with one hole with the trip associated with another hole.

2. An electric receptacle provided with an insulating portion forming holes adapted to receive the connection prongs of an attachment plug, a spring-closed door for each hole, at least two locking means associated with each door, any one of which serves to hold said door closed, and 10 releasing means associated with each hole operated by the insertion of a connection prong therein to release only one of the locking means simultaneously for each door.

3. An electric receptacle which comprises a 15 housing, electrically charged terminals secured within said housing, said housing having holes in a wall thereof in alignment with said electrically charged terminals through which the prongs of a connection plug may be inserted to engage said 20 electrically charged terminals, and means in the housing operable to shield said terminals from contact through the openings, said means including a movable door interposed between each terminal and the hole leading thereto and normally 25 closing the hole, a locking device for each door operable to hold the door in closed position, and trips in the housing, each trip having a portion exposed in one of the holes for engagement and operation by a connection prong when inserted 30 through said opening, each trip being operable to render inoperative the locking device for a door closing an opening different from that in which said trip is exposed.

4. An electric receptacle which comprises a 35 housing, electrically charged terminals secured within said housing, said housing have holes in a wall thereof in alignment with said electrically charged terminals through which the prongs of a connection plug may be inserted to engage said 40 electrically charged terminals, and means in the housing operable to shield the terminals from contact through the holes, said means including a movable door interposed between each terminal and the hole leading thereto and normally 45 closing the hole, a plurality of locking devices, the same in number as the doors, each device being operable to prevent movement of a plurality of doors from closed position, and trips in the housing, each trip having a portion exposed in 50 an opening for engagement and operation by a connection prong when inserted through said opening, each trip being operable to render a locking device inoperative.

5. An electric receptacle which comprises a 55 housing, electrically charged spring terminals secured within said housing, said housing having holes in a wall thereof in alignment with said spring terminals through which the prongs of a connection plug may be inserted to engage 60 said spring terminals, a spring-closed door for each hole displaceable by pressure exerted thereon by a connection prong moving therethrough in a single direction towards said spring terminals, two locking means associated with each 65 door, each of which serves to hold said door closed, and releasing means associated with each hole for operation by the insertion of a connection 70 prong therein to release one of said two locking means simultaneously for each of said doors, thereby to permit said connection prongs to engage said spring terminals.

6. An electric receptacle provided with an insulating portion forming at least two spaced holes adapted to receive a like number of connection 75 prongs of an attachment plug, a spring-closed

door for each of said two holes hinged between said holes in spaced relation, each door having a surface which effectively opens said hole by swinging away therefrom, and a portion which swings into the space between said doors, locking 5 dogs positioned in said space, each of which serves to prevent both of said doors from swinging, and a trip associated with each of said two holes, each trip being attached to a different one of said dogs and being operated by the insertion 10 of a connection prong in its respective hole to move the dog to which said trip is attached, whereby the insertion of connection prongs in both of said holes releases both of said doors to open.

7. An electric receptacle provided with an insulating portion forming two rectangular oblong holes spaced with their long axes at right angles to each other and adapted to receive the connection prongs of a polarized attachment plug, a 20 spring-closed door for each hole hinged substantially parallel to the long axis of the hole with which it is associated, each door having a surface which effectively opens said hole by swinging away therefrom, a trip associated with each 25 of said holes, two shafts, one attached to each trip, each trip being operated by the insertion of a connection prong in its respective hole to rotate the shaft to which said trip is attached, a dog and a latch being secured to one shaft and 30 a dog and a locking strap being secured to the other shaft, both of said dogs being operative to lock and release one of said doors, and said latch and said strap being operative, in cooperation with a shoulder and a pin positioned, respectively, 35 on opposite sides of the other of said doors, to lock and release said last-named door.

8. In an electric receptacle, an insulating portion forming at least two holes adapted to receive the connection prongs of an attachment 40 plug, a slide member having portions effective to close said holes and cam-like surfaces cooperating with said connection prongs to displace said slide member thereby effectively to open said holes, at least two locking means serving to lock 45 said slide member in closed position, and separate releasing means for said locking means, one associated with each of said holes, said releasing means being operated by the insertion of said connection prongs in said holes to release said locking means.

9. In an electric receptacle, an insulating portion forming two holes adapted to receive the connection prongs of an attachment plug, a slide member of insulating material having portions 55 effective to close said holes, said portions having cam-like surfaces cooperating with said connection prongs to displace said slide member thereby effectively to open said holes, two locking means serving to lock said slide member in closed position, and separate releasing means for said locking 60 means, one associated with each of said holes, each of said releasing means being attached to a different one of said locking means and being operated by the insertion of said connection 65 prongs in said holes respectively to release said locking means.

10. An electric receptacle provided with an insulating portion forming two holes adapted to receive the connection prongs of an attachment 70 plug, contact springs positioned in alignment with said holes, a spring-closed slide member secured beneath said holes having cam-like door surfaces effectively closing said holes, two locking holes in said slide member and two latches co- 75

operating therewith to lock said member with the door surfaces in closed position, a trip associated with each of said prong-receiving holes, each trip being attached to one of said latches, and both trips being operated by the insertion of said connection prongs in their respective holes to release said latches and to permit said slide member to be moved against said spring by the pressure of said prongs on said cam-like door surfaces, whereby said prong-receiving holes are opened to permit said prongs to engage said contact springs.

11. An electric receptacle which comprises a housing, electrically charged spring terminals secured within said housing, said housing having holes in the wall thereof in alignment with said spring terminals through which the prongs of a connection plug may be inserted to engage said spring terminals, a spring closed door for each hole having a cam-like face displaceable by pressure exerted by a connection prong moving in the direction of insertion, a plurality of independent locking means associated with each door serving to hold each door closed, and releasing means associated with each hole operated by insertion 25 therein of a connection prong to release one of

said plurality of locking means simultaneously for each of said doors, thereby to permit said connection prongs to displace said doors and to engage said terminals by continued insertion in the same direction.

12. An electric receptacle which comprises a housing, electrically charged terminals within said housing, said housing having a plurality of holes in a wall thereof through which the prongs of a connection plug may be inserted to engage 10 said electrically charged terminals, a door portion and a trip associated with each hole, each door portion being provided with at least one locking means serving to lock said door portion in a position effectively closing the hole with which it is associated, and means operatively connecting the locking means which locks the door portion associated with each one of said holes with the trip associated with another of said holes, whereby insertion of a connection prong in any one hole 15 actuates the trip associated with that hole and releases the locking means associated with another hole.

GLENN E. BLINN. 25
